LINER FOR A PICKUP TRUCK

Jack V. Ritter, Puyallup, Wash., assignor to Research
Marketing, Inc.

Filed Apr. 27, 1970, Ser. No. 22,676

Term of patent 14 years

Int. Cl. D12—16

U.S. Cl. D14—6

FIG. 1

FIG. 2

FIG. 3

FIG. 4

FIG. 5

FIG. 6

FIG. 1 is a perspective view looking down at the inside of a liner for a pickup truck;

FIG. 2 is a top plan view looking down on said liner;

FIG. 3 is a side elevation view of said liner;

FIG. 4 is an underneath plan view of said liner;

FIG. 5 is an end view of said liner and looking at the open end of said liner; and

FIG. 6 is an end view of said liner looking at the closed end of said liner.

I claim:

The ornamental design for a liner for a pickup truck, substantially as shown.
